UNITED STATES PATENT OFFICE.

MICHAEL J. CAHILL AND WILLIE H. REYNOLDS, OF CHICAGO, ILLINOIS.

DESIGN FOR A WHEEL.

SPECIFICATION forming part of Design No. 27,078, dated May 18, 1897.

Application filed December 5, 1896. Serial No. 614,661. Term of patent 14 years.

To all whom it may concern:

Be it known that we, MICHAEL J. CAHILL and WILLIE H. REYNOLDS, citizens of the United States, residing at Chicago, in the county of Cook and State of Illinois, have invented and produced a certain new and original Design for Air-Motor Wheels; and we do declare the following to be a full, clear, and exact description of the invention, such as will enable others skilled in the art to which it appertains to make and use the same.

Our invention relates to a new and useful design for a rotating wheel for compressed-air motors.

It relates to the entire configuration of the wheel.

Our invention relates particularly to the motor-wheel as illustrated in the accompanying drawings, in which—

Figure 1 is a perspective view of an air-motor wheel embodying our design. Fig. 2 is an edge view, and Fig. 3 is a longitudinal section of the same.

The leading features of our design appear in the following description.

1 1 represent the parallel sides of the wheel, and they are circular or disk-shaped with plane parallel faces, as shown.

2 represents a cylindrical orifice, extending transversely through the center of the wheel. 30 The rim or periphery of the wheel consists of a series of curved pockets 3 3, each of which has a scroll-shaped bottom 4, extending between the sides 1 1, as shown.

Having thus fully described our invention, 35 what we claim as new and useful to secure by Design Letters Patent of the United States is—

The design for an air-motor wheel, substantially as herein shown and described. 40

In testimony whereof we hereunto affix our signatures in presence of two witnesses.

MICHAEL J. CAHILL.
WILLIE H. REYNOLDS.

Witnesses:

W. E. KEELEY,
M. L. MCKINLEY.
